UNITED STATES PATENT OFFICE.

FRANZ TRINKS AND FERDINAND STEMMLER, OF BRUNSWICK, GERMANY.

COMPUTING OR CALCULATING MACHINE.

1,194,900.

Specification of Letters Patent. Patented Aug. 15, 1916.

Application filed January 4, 1916. Serial No. 70,229.

To all whom it may concern:

Be it known that we, FRANZ TRINKS, manufacturer, and FERDINAND STEMMLER, workmaster, citizens of the Duchy of Brunswick, Empire of Germany, residing at Brunswick, Germany, have invented certain new and useful Improvements in Computing or Calculating Machines of which the following is a specification.

10 This invention relates to computing or calculating machines, and in particular to computing machines of the class having shiftable operating teeth for setting up numbers and items in the machine.

15 The object of our invention is to provide in machines of this class actuating means for automatically preventing, during the operation of the main operating lever, alterations in the setting of the operating teeth which 20 have been previously shifted into operative position, and to provide actuating means to permit the operating teeth to be shifted for setting up numbers and items.

25 Referring to the accompanying drawings, in which an embodiment of our invention is illustrated by way of example: Figure 1 represents a transverse section of a computing machine embodying the invention. Fig. 2 is a view, similar to Fig. 1 of a part of the 30 setting-up mechanism but showing some parts in a different relative position. Fig. 3 is a plan view partly in section of the machine with the larger number of parts removed, only the parts necessary for the 35 proper understanding of this invention being shown. Fig. 4 is an end view of a detent device which forms a part of this invention.

The machine for which our invention is particularly applicable is of the type described in U. S. Patent No. 946,367, and the 40 present invention is shown in the drawings and will be described as applied to a machine of such a type. The operating teeth 11 are slidably mounted in the disk 6 which 45 is fixedly secured upon the shaft 4, the said operating teeth 11 being adapted to be shifted into operative position by means of a cam groove 12 in the disk 7 which is mounted coaxially with the disk 6 but which may be 50 moved independently of the disk 6 by means of the lever or handle 15. The cam disk 7 is provided with circularly disposed indentations 14 which are engaged by a spring actuated pin 13 slidably mounted in the disk 55 6. The wedge shaped tip of the said pin 13 corresponds to the shape of the indentations

14 which are spaced apart so as to correspond to the division and number of the operative teeth 11 in the disk 6. In revolving the said cam disk 7 the yieldable locking pin 13 is moved radially inward until the next indentation 14 is in position to be engaged by the said pin, in which position the cam disk 7 is then locked unless the resistance of the spring of the locking pin 60 13 is again overcome to permit the cam disk 7 to be advanced another step. Thus, the stations of the cam disk 7 are determined by the position of the indentations 14 which correspond to the number and division of 65 the operating teeth 11 in the disk 6. This prevents any of the operating teeth 11 from being but partly projected when being shifted into operative position.

Our invention consists in making the shaft 75 4 tubular and mounting within such tubular shaft a rotatable shaft *h*. The shaft 4 is provided with radial openings *j* into which project, and in which are guided, the stems of the pins 13, when the latter are in their 80 normal locking position. Radial holes *i* are formed in the inner shaft *h*, which holes *i* correspond in number to the openings *j* of the shaft 4 and are positioned to register with the said openings *j* when the inner shaft *h*, 85 for that purpose, is turned relatively to the outer shaft 4. The stems of the pins 13 are of such a length that the inner end must enter into the bore hole *i* to permit the outer wedge shaped end of the pin 13 to ride over 90 any one of the teeth formed by the indentations 14 in the cam disk 7.

When the desired number of operating teeth are shifted into operative position and the main machine handle 18 which actuates the shaft 4 and the plurality of disks 6 through a pair of gear wheels 19, 20, is to be operated, a novel device comes into operation for automatically locking each of the cam disks 7 in its set position to the disk 6, 100 which device will now be explained.

As shown in Fig. 3, the inner shaft *h* is provided at one end with a helical spring *h*¹ which has one end secured to a stationary 105 part of the machine frame and tends to turn the shaft *h* into the position shown in Fig. 1 in which the bore holes *i* are out of register with the openings *j* in the tubular shaft 4. This position of the inner shaft *h* with respect to the outer shaft 4 may be called the 110 normal locking position in which none of the operating teeth 11 can be set up since the

cam disks are locked against independent rotation. When it is desired to shift operating teeth into operative position, the inner shaft h must first be moved into inoperative position for which the following mechanism is provided: Parallel to the shafts 4 and h there is mounted in the machine frame a 5 slidable rod w provided with a spring r^1 that tends to move the rod w toward the right hand end of the machine where a slide v is mounted in stationary guides u^1 and u^2 . This slide v has an oblique operating face v^1 against which the end of the rod w bears under the action of the spring r^1 . When the 10 said slide v is manually moved in the direction of the arrow in Fig. 3 and against the action of the spring r^2 located within the guide u^1 , the said oblique operating face v^1 of the slide v rides over the end of the slidable rod w which is thereby moved toward the 15 opposite side of the machine, where the rod w is provided with an oblique operating face w^1 which bears against a lever e fixedly connected to a projecting end of the inner shaft h . When the rod w is moved to the left the lever e is caused to rock the inner shaft h which thereupon assumes the position shown in Fig. 2 in which the bore hole i registers with the opening j in the outer shaft 4 . In 20 this position, the shaft h is retained by a detent or latch z provided preferably at the same end of the machine as the operating handle 18. The latch arm z is pivotally mounted at the side of the stationary machine frame and is under the influence of a 25 suitable spring which tends to hold the latch arm z in engagement with a notch provided in a collar n which is fixedly secured upon the inner shaft h . The operative position of the 30 detent or latch z is illustrated in Fig. 4, in which the shaft h is in the same position shown in Fig. 2 and in which the openings i and j are in register to permit the teeth 14 to ride over the pin B and thus permit of 35 setting up any desired number of operating teeth 11. As shown in Fig. 4 the detent z is provided with another arm s adapted to be engaged by a cam t which is secured upon the shaft 17 of the main operating handle 40 and revolves with the latter. The arm s serves to release the detent z when the operating handle 18, and incidentally the cam t , is being revolved. When thus released, the inner shaft h will, by the action of the 45 helical spring h^1 be restored to the normal locking position shown in Fig. 1 and in which the yieldably mounted locking pin 13 is prevented by the unbored portion of the inner shaft h from moving radially inward, 50 so that the cam disk 7 is locked and cannot be shifted independently of the teeth bearing disk 6 .

When it is desired to again unlock the locking pin 13 and render the same yieldable, it is only necessary to push the slide v

in the direction indicated by the arrow in Fig. 3, whereupon the shaft h is again caused, through the agency of the bar w and the arm e , to rock into the position in which the detent z becomes operative to retain the said shaft until automatically released through 70 operation of the handle 18.

While we have shown in the drawings suitable structural means for carrying our invention into effect, we desire it to be 75 understood that the said means may be structurally varied within wide limits without departure from the scope and spirit of our invention.

What we claim and desire to secure by 80 Letters Patent of the United States, is:

1. In a computing machine, the combination of a tubular revoluble shaft; a disk mounted on said shaft having operating teeth slidably mounted therein; a second 85 disk mounted coaxially with and in proximity to said first disk and adapted, when rotated relative to the latter, to shift said teeth into operative position, said second disk having indentations corresponding in 90 number and position to the teeth in the first disk; a spring-actuated locking pin slidably mounted in said first disk and adapted to engage the indentations in said second disk; said tubular shaft having a radial aperture 95 to receive one end of said locking pin; a shaft mounted within said tubular shaft and having a radial depression adapted, when said inner shaft is rocked, to be brought into register with said aperture in said tubular 100 shaft to permit the inner end of said locking pin to enter said depression and the outer end of said locking pin to ride over said indentations when said second disk is being rotated; an arm on said inner shaft; 105 means for rocking said arm to bring the depression in the inner shaft into register with the aperture in the tubular shaft; and a spring actuated detent for retaining said last-mentioned shaft in said last mentioned 110 position.

2. In a computing machine, the combination of a revoluble shaft having a radial opening; an actuating lever operatively connected to said shaft; a disk mounted on said 115 shaft having operating teeth slidably mounted therein; a second disk mounted coaxially with and in proximity to said first disk and adapted to shift said teeth into operative position, said second disk having indentations corresponding in number and position to the teeth in said first disk; a spring-actuated locking pin slidably mounted in said 120 first disk and having its lower end projecting into the opening of said tubular shaft and its upper end adapted to engage the indentations in said second disk; said inner shaft having a depression adapted, when the latter shaft is rocked, to be brought into 125 register with the radial opening in said 130

- tubular shaft and receive the inner end of said locking pin and permit the outer end of said locking pin to ride over said indentations when said second shaft is rocked; an 5 arm on said inner shaft; a pair of coöperating spring-actuated slides to oscillate said arm; a spring-actuated detent for retaining said inner shaft in rocked position and actuated by said actuating lever in the initial 10 part of its movement for releasing said detent.
3. In a computing machine, a revoluble tubular shaft; a plurality of sliding number-operating teeth carried by said shaft; means 15 mounted on said shaft adapted, when actuated, to shift said teeth into and out of operative position; means carried by said tubular shaft to lock said teeth-shifting means thereto in set position; a rock shaft within 20 said tubular shaft coöperating with said locking means and adapted, when in normal position, to maintain said locking means in locked position and when in rocked position to release said locking means; means tending 25 to maintain said rock shaft in the former position; means for rocking said rock shaft into unlocking position; and means for securing the rock shaft in rocked position.
- 30 4. In a computing machine, a revoluble tubular shaft; a plurality of sliding number-operating teeth carried by said shaft; means mounted on said shaft adapted, when actuated, to shift said teeth into and out of operative position; means carried by said tubular shaft to lock said teeth-shifting means thereto in set position; a rock shaft within 35 said tubular shaft coöperating with said locking means and adapted, when rocked, to release said locking means and when in normal position to secure said locking means; means tending to maintain said rock shaft in the latter position; means for rock-
- ing said rock shaft into unlocking position; means for securing said rock shaft in rocked 45 position; and means coöperating with said tubular shaft adapted, when the latter is restored to normal position, to release said rock shaft securing means.
5. In a computing machine, a revoluble 50 tubular shaft having a radial opening; a spring-actuated plunger mounted in said radial opening; a plurality of sliding number-operating teeth carried by said shaft; means rotatably mounted on said shaft 55 adapted, when actuated, to shift said teeth into and out of operative position and having indentations for engagement by said plunger to lock said teeth-shifting means to said tubular shaft; a rock shaft mounted 60 within said tubular shaft and having a radial depression adapted, when said shaft is rocked, to be brought into register with the radial opening of said tubular shaft to receive said plunger and permit the indentations 65 of the teeth-shifting means to ride over said plunger; means normally tending to rock said inner shaft into a position with its radial depression out of register with the opening of the tubular shaft; means to rock 70 said inner shaft to bring its radial depression into register with the radial opening of the tubular shaft; means to automatically secure said inner shaft in its latter position, and means associated with said tubular shaft 75 adapted, when the latter shaft is rotated, to release said securing means.

In testimony whereof we have hereunto set our hands in presence of two subscribing witnesses.
